ATTORNEY.

UNITED STATES PATENT OFFICE.

ANDREW A. BRENGEL, OF JERSEY CITY, NEW JERSEY.

DESIGN FOR A CURTAIN-HANGER.

SPECIFICATION forming part of Design No. 29,669, dated November 15, 1898.

Application filed October 21, 1898. Serial No. 694,237. Term of patent 3½ years.

To all whom it may concern:

Be it known that I, ANDREW A. BRENGEL, a citizen of the United States, and a resident of Jersey City, county of Hudson, and State 5 of New Jersey, have invented a certain new and original Design in Curtain-Hangers, of which the following is a specification, reference being had to the accompanying drawings, forming a part thereof, in which similar letters of reference indicate corresponding parts.

Figure 1 is a perspective view of the curtain-hanger, showing my new design. Fig. 2 is a cross-sectional view of the same.

As shown in the drawings, the leading or 15 material feature of my design consists of a flat upper face *a*, a series of beads or ribs *b b* upon the sides of the hanger, said ribs or beads *b b* being convex in cross-section, and

a longitudinal channel *c*, cut through the lower face and communicating with a rectangular chamber *d*, extending the full length of the hanger. 20

Having described my invention, what I claim as new, and desire to secure by Letters Patent, is—

The design for a curtain-hanger, as herein shown and described.

In testimony that I claim the foregoing as my invention I have signed my name, in presence of two witnesses, this 19th day of October, 1898. 30

ANDREW A. BRENGEL.

Witnesses:

SYDNEY D. PRESCOTT,
BELLE McCOMB.
